Application February 5, 1953, Serial No. 23,456

Term of patent 14 years

(Cl. D48—20)

To all whom it may concern:

Be it known that I, Benedictus K. Kaveckas, a citizen of the United States, residing at Roselle, State of New Jersey, have invented a new, original, and ornamental Design for an Infrared Ray Lamp, of which the following is a specification, reference being had to the accompanying drawing, forming a part hereof.

The figure is a perspective view of an infrared ray lamp, showing my new design.

The dominant features of my new design reside in the configuration of the lamp unit.

I claim:

The ornamental design for an infrared ray lamp, as shown and described.

BENEDICTUS K. KAVECKAS.
